BOTTLE CAP

John C. Terry, Hollywood, Calif.

Application July 2, 1946, Serial No. 681,001

6 Claims. (Cl. 215—45)

1

This invention relates to a bottle cap and it is primarily an object of the invention to provide a cap of this kind which can be removably applied and which, when in working position, affords a gas-tight seal.

Furthermore, it is an object of the invention to provide a device of this kind which is particularly advantageous for use in connection with bottles having an outside bead at the discharge end of the bottle neck, such as is provided in the well known type of milk bottles.

An additional object of the invention is to provide a cap which is effectively held in applied position under the action of a lever mounted upon the cap and which has associated therewith a bead-engaging hook member possessing a certain degree of inherent resiliency.

The invention consists in the details of construction and in the combination and arrangement of the several parts of my improved bottle cap whereby certain important advantages are attained, as will be hereinafter more fully set forth.

In order that my invention may be better understood, I will now proceed to describe the same with reference to the accompanying drawings, wherein:

Figure 1 is a view in side elevation illustrating a bottle cap constructed in accordance with an embodiment of the invention and in applied position, the associated container being in fragment;

Figure 2 is a view in top plan of the cap as herein embodied, with the lever and hook member omitted;

Figure 3 is a sectional view taken substantially on the line 3—3 of Figure 2;

Figure 4 is a sectional view taken substantially on the line 4—4 of Figure 2;

Figure 5 is a view in plan of the blank from which the body of the cap is formed;

Figure 6 is a view in top plan of the cap as herein embodied, with the lever in an intermediate position;

Figure 7 is a view in top plan of the blank of the lever as herein embodied;

Figure 8 is a view in top plan of the lever, unapplied;

Figure 9 is a sectional view taken substantially on the line 9—9 of Figure 8;

Figure 10 is a view in plan of the hook member as herein embodied, unapplied; and

Figure 11 is a sectional view taken substantially on the line 11—11 of Figure 10.

In the embodiment of the invention as illustrated in the accompanying drawings, the body 55

2

member B of the cap is formed from one sheet of material of requisite dimensions, as is clearly illustrated in Figure 5 of the drawings. This body member B comprises a central circular head 1 of desired radius and which is provided at one point on its periphery with an extended tongue 2 which is rolled back upon itself to provide a pivotal mounting for the lever L, as will be herein-after more particularly set forth.

10 Diametrically opposed to the tongue 2, the head 1 is provided with an extended flange 3 which is upwardly turned on the line a (Figure 5) to substantially right angles to the head 1. This flange 3 along the major portion thereof is provided 15 with the slot 4, the inner edge of which is coplanar with the line a, as is also clearly shown in Figure 5. This slotted flange 3 provides an effective guide for the hook member H to be herein-after more particularly referred to.

20 Between the tongue 2 and the flange 3 the periphery of the head 1 is defined by the flanges 5 extending substantially the entire distance between the tongue 2 and the flange 3 at opposite sides thereof. These flanges 5 are turned downwardly substantially at right angles with respect to the head 1 and the end portion of the flanges 5 adjacent to the tongue 2 is increased in width, as at 6, said portion extending around the head 1 to a point about 60° remote from the transverse 25 center of the tongue 2.

The outer marginal portion 7 of each of the enlargements 6 is disposed inwardly on a slight curvature so as to engage under the conventional external bead 8 generally found at the outer or 30 discharge extremity of a bottle neck 9, such as the type used in connection with milk and the like.

The lever L, as illustrated in Figures 7 and 8, is also formed from a single blank or sheet of 35 material and includes a flat shank 10 provided along its longitudinal or side edges with the wings 11 which are turned substantially at right angles to the shank 10. These wings 11, as herein disclosed, are substantially triangular in form 45 with their apices inwardly disposed and the outer high points of the wings 11 are provided there-through with the openings 12 which are in trans-verse alignment.

The shank 10 in its outer end in substantially 50 the same plane as the openings 12 is provided transversely thereof with the slot 14 through which the tongue 2 is freely directed, whereby the lever L is mounted upon the body of the cap for required swinging or rocking movement. The outer end of the lever L has integrally formed

therewith a flattened finger plate or piece 15 disposed on an angle of approximately 15° with respect to the shank 10 and said angle being in the same general direction as that of the wings 11.

The adjacent central portion of the shank 10 and the plate 15 have pressed outwardly therefrom a strengthening or reinforcing bead or rib 16 whereby the plate 15 and shank 10 are effectively reinforced against bending as a result of the strain or stress imposed upon the head plate or piece 15 in either applying or removing the cap.

The hook member H, as particularly illustrated in Figures 10 and 11, is formed from a single length of spring wire of requisite gauge formed to provide the elongated parallel side arms 17 in predetermined spaced relation and coextensive in length one with the other. The adjacent extremities of these arms 17 are free but are continued by the inwardly disposed and transversely aligned trunnions 18 which are disposed from without through the openings 12 in the wings 11 whereby the hook member H is operatively engaged with the lever L whereby the hook member H will have substantial endwise movement in either direction across the body of the cap, depending upon the rocking or swinging movement of the lever L. It is to be noted that the portions of the arms 17 immediately adjacent to the trunnions 18 are disposed on an inward incline, as at 19, on preferably an angle of 15° with respect to the major portion of the arms 17.

The extremities of the arm 17 remote from the trunnions 18 are integrally connected by a cross member formed to provide an inwardly facing hook bill 20 disposed preferably on an angle preferably of 45° with respect to the arms and which bill 20, when the lever L is at the limit of its movement inwardly of the body 1, is adapted to engage under the bead 8 of the container 9 when the lever is swung outwardly and downwardly to lie close against the side of the container, as clearly illustrated in Figure 1 of the drawings. When the lever L is in its downward or locking position, the cap as a unit is effectively held in applied position on the container 9 and which position is further assured by the inherent resiliency of the hook member H and more particularly the bill 20 thereof.

In close contact with the inner face of the head 1 and snugly held between the flanges 5 is a sealing disk 21 of rubber or other suitable material and which disk 21 has direct contact with the outer edge surface of the container when the cap is applied thereto.

Before the hook member H is operatively engaged with the lever L, the arms 17 thereof are threaded through the slot 4 of the flange 3, whereby said hook member is effectively guided in its movement substantially radially across the head 1. It is also to be pointed out that the slot 4 is of a length whereby the flange 3 also provides an effective means for holding the arms 17 against outward separating movement, whereby accidental disengagement of the trunnions 18 with the wings 11 of the lever L is substantially eliminated.

When the lever L is in released position, and with the cap in initially applied position on the container 9 the flanges 5 of the head 1 and the

bill 20 of the hook member H contact the head of the container 9 at a point slightly below the center of the radius and at which time the ceiling disk or gasket 21 is not under compression. 5 When the lever L is moved inwardly or downwardly, the bill 20 of the hook member H also moves downwardly whereby the disk or gasket 21 is put under compression to effect a gas tight seal between the container and cap.

10 From the foregoing description it is thought to be obvious that a bottle cap constructed in accordance with my invention is particularly well adapted for use by reason of the convenience and facility with which it may be assembled and operated.

I claim:

1. A cap for a container having a neck with an exterior bead around the outer end of said neck, said cap comprising a head, marginal flanges carried by the head, said flanges having portions to engage under the external bead of the container, a lever engaged with a marginal portion of the head for swinging movement, and a hook member extending across the head and operatively engaged with the lever, said hook member having an inwardly disposed bill to engage the external bead of the container when the lever is swung in one direction.

2. A cap as set forth in claim 1, wherein the head at a point diametrically opposed to the mounting of the lever is provided with a guiding means for the hook member.

3. A cap as set forth in claim 1, wherein the connection between the head and lever comprises a tongue extending from the head and returned upon itself, an end portion of the lever being provided with a slot through which the tongue is freely disposed.

4. A cap as set forth in claim 1, wherein the head at a point diametrically opposed to the mounting for the lever is provided with an outstanding flange having a slot, the hook member being disposed through the slot whereby said flange constitutes a guide for the hook member.

5. A cap as set forth in claim 1, wherein the hook member comprises spaced elongated side members having free extremities terminating in inwardly disposed trunnions engageable with the lever, and an outstanding flange carried by the head having a slot through which the hook member passes, said slotted flange providing a guide for the movement of the hook member across the head and also holding the side arms of the hook member against outward separating movement to maintain the trunnions in operative engagement with the lever.

6. A cap as set forth in claim 1, wherein a compressible gasket overlies the underface of the cap, the flanges of the head and the bill of the hook member contact the head of the container at a point slightly below the center of the radius when the lever is in release position and the gasket is not under compression, the bill of the hook member moving downwardly when the lever is closed to put the gasket under compression to effect a gas tight seal between the container and cap.

JOHN C. TERRY.
